CIRCUIT INTERRUPTER

Joseph Slepian, Pittsburgh, Pa., assignor to Westinghouse Electric & Manufacturing Company, a corporation of Pennsylvania

Application October 13, 1931, Serial No. 568,554
Renewed October 1, 1935

45 Claims. (CL. 200—144)

My invention relates to circuit interrupters and more particularly to the type in which the arc is drawn in and expulsion chamber through which a blast of gas is passed to extinguish the arc.

5 An object of my invention is to provide a circuit interrupter in which a deionizing blast of gas for extinguishing the arc is caused by the decomposition of a solid material which gives off a non-inflammable condensable gas when acted 10 on by the arc. This may be accomplished by using blocks of boric acid which give off water vapor in large quantities when acted upon by the arc. Boric acid is a most desirable material for this 15 purpose due to the fact that it may be compressed into solid cakes which may be arranged along the arc path. Further advantages of the use of boric acid lie in the fact that it is non-hygroscopic so that it maintains its insulating properties where the air is damp, and in that it remains 20 a good insulator even when its surface is molten.

Another object of my invention is to provide a circuit interrupter in which the arc is drawn between a pair of closely spaced walls which reduce 25 the cross section of the arc and cause it to take the form of a thin sheet having a large area of contact with the walls, thus providing surfaces which aid the deionization of the arc. In addition, the closely spaced walls provide that a maximum 30 amount of material is in contact with the arc so that it may be decomposed, giving off a large volume of gas to extinguish the arc by causing turbulence, so that quantities of cool, un-ionized gas are in-mixed with the hot arc gases 35 to deionize them.

40 A further object of my invention is to provide a circuit interrupter of the expulsion type which is open at one end only so as to cause a longitudinal flow of gas through the arc stream to deionize it.

45 A further object of my invention is to provide a condenser over the opening from the expulsion chamber so as to condense the gases which are expelled. This makes it possible to make the circuit interrupter completely closed, and at the same time avoid building up high pressures within the arc chamber. A further advantage of this construction lies in the fact that there are no gases exhausted from the device so that there 50 is no danger of flash-over due to the hot ionized gases coming in contact with adjacent apparatus. This use of a condenser makes possible a completely closed device without sacrificing the advantages of a flow of gas through the arc, out 55 the end of an expulsion chamber.

In general, the circuit interrupter of my invention comprises a tubular enclosing member which is lined on the inside with solid members of boric acid having rectangular openings therethrough. A fuse element or a movable contact rod is actuated by any suitable means through this opening to draw the arc. The arc is thus drawn in contact with the walls of the boric acid members causing the boric acid to be decomposed and give off water vapor which flows longitudinally through the arc and out the end of the expulsion chamber into a closed condenser secured to the end of the tubular enclosing member.

5 The circuit interrupter of my invention has important advantages over circuit interrupters which use oil as the arc extinguishing medium in that the oil is inflammable, thus causing a considerable fire risk, and also provides a much simpler structure, since no tanks for holding the oil are required. Another important advantage over oil 10 circuit breakers, and over circuit interrupters in which the expulsion action is obtained by decomposition of fiber, is that the gas given off with the circuit interrupter of my invention is not inflammable and is condensable which is not true 15 of the gases given off from either oil or organic insulating materials such as fiber. An analysis 20 of the gases given off from fiber shows that they 25 are largely hydrogen and carbon monoxide, which are permanent gases not readily condensed and 30 are inflammable.

35 My circuit interrupter gives a much desired improvement over devices which use water in the liquid state as the arc extinguishing medium, in that liquid-tight containers must be provided for the water, and that the liquid water evaporates thus making it necessary to continually replace it in order to keep the circuit interrupter in readiness to extinguish an arc at any time. My circuit 40 interrupter is also desirable in that it is entirely self-contained and does not require the use of storage tanks for holding compressed gas for the purpose of extinguishing the arc. Devices using a supply of compressed gas are always dangerous, due to the fact that the supply of gas 45 may fail at just the time when it is necessary to extinguish the arc.

These and other objects and advantages of my invention will be more fully apparent from the following description of the drawing which 50 illustrates a specific embodiment of the invention, and in which

55 Figure 1 is a longitudinal sectional view through a fuse constructed according to the principles of my invention.

Fig. 2 is a transverse sectional view through the condenser of Fig. 1 taken on the line II—II thereof.

Fig. 3 is a transverse sectional view through the arc extinguishing chamber taken on the line III—III of Fig. 1, and

Fig. 4 is a partial longitudinal sectional view similar to Fig. 1 but showing a circuit breaker constructed according to my invention.

10 The fuse illustrated in Figs. 1, 2 and 3 comprises an outer tubular casing 5 of fibre or any other suitable insulating material and has metal terminal members 7 and 9 to which electrical connection to the fuse is made. The terminal member 7 comprises a cap which is suitably secured to the tube 5, as by a screw thread, and is provided with an opening 11 in the end thereof. The cap 9 is removably secured to a sleeve 13 which is suitably fastened, as by a screw thread, 20 to the tubular casing 5.

Within the fibre tube 5 is placed a plurality of cakes 15 of an insulating material which has the property of providing a non-inflammable, condensable gas when acted upon by an arc. While 25 various materials may be used to provide the deionizing gas, it has been found that materials such as boric acid, gypsum, and ammonium alum give desirable results. Of these materials it has been found that boric acid is by far the most desirable, since its properties are such as to give best results. It has been found that boric acid may be readily compressed into cakes by the application of pressure and that these cakes have such mechanical strength that they may be used 35 in circuit interrupters without difficulty. When boric acid (H_3BO_3) is acted upon by the arc, it is decomposed giving off water vapor (H_2O) leaving boric oxide (B_2O_3). Boric acid also has the advantage that it is an extremely good insulator and that it retains its insulating properties even when it has been heated to a high 40 temperature and is in a molten state. Another very desirable property of boric acid is that it is non-hygroscopic, thus repelling water so that it 45 does not lose its insulating properties when placed in a humid atmosphere.

For some applications, it has been found that a desirable material for giving off the deionizing gas is gypsum ($CaSO_4 \cdot 2H_2O$) which is a calcium sulphate having water combined therewith. This 50 material is decomposed by the arc giving off water vapor (H_2O), sulphur dioxide (SO_2) and oxygen (O_2) leaving a solid calcium oxide (CaO). While gypsum does not give results anywhere 55 near as good as boric acid, it may be used in circuit interrupters where very high interrupting capacities are not necessary.

Another material which may be used in some constructions is ammonium alum

60 $(Al_2(NH_4)_2(SO_4)_4 \cdot 24H_2O$.

This is decomposed by the arc giving off water vapor (H_2O), sulphur dioxide (SO_2), ammonia (NH_3) and leaving the solid aluminum oxide 65 (Al_2O_3). In general, ammonium alum is not as satisfactory a material as boric acid due to the fact that it is necessary for the un-decomposed portions of the walls of the gas generating members to withstand the full circuit voltage after 70 the arc is extinguished, with the passage of little current. It therefore must be a good insulator, not only when cold, but also when at the high temperature at which rapid decomposition takes place, since the surface of the material will be 75 at this high temperature at the moment arc ex-

tinction takes place. This explains why boric acid is more effective than ammonium alum, since boric acid has a high resistivity even at a temperature of several hundred degrees centigrade at which it decomposes rapidly. Ammonium alum is superior to boric acid from the standpoint of volume of gas evolved but when tested in an expulsion fuse of the type illustrated, it is much inferior as to its voltage interrupting capacity. While ammonium alum is 10 a good insulator when cold, it melts at 89° C. and becomes a good conductor. It loses water rapidly at 150° C. so that this may be taken for the temperature of rapid decomposition. This means that the surface left immediately after 15 the arc extinction will be an electrically conducting film of the molten salt which will break down under voltage and restart the arc, unless especial constructions are used to provide other insulation along the arc path. It is thus seen 20 that boric acid is a most desirable material and gives the highest voltage interrupting capacity due to the fact that it combines all of the desirable properties which such an arc extinguishing material should have. 25

Each of the blocks of arc extinguishing material 15 is provided with an opening 17 in the shape of a rectangle which is of several times greater breadth than width, and is of such width that it constricts the cross section of the arc and causes it to spread out in the form of a thin sheet so that there is a large area of the arc in intimate contact with the cold walls of the boric acid. This large surface aids the deionization of the arc and in addition makes possible the rapid decomposition of the boric acid or other arc extinguishing material so that a large quantity of deionizing gas is evolved. Experimental results show that such a narrow rectangular cross section is much superior to a circular section, for example, tests have been made with a slot $1/8'' \times 1\frac{3}{4}''$ showing that 2100 volts per inch 30 could be interrupted at 450 amperes while a hole with a circular section of the same area having a diameter of 0.53 inch was able to interrupt 35 only 400 volts per inch. This shows that the rectangular section was over five times as effective as the circular section. 40

The rectangular openings 17 in the boric acid blocks 15 are all aligned and form a long, narrow chamber in which the arc may be extinguished. A fusible element 19, having a reduced section 21 which is melted upon the occurrence of excess current, extends through the chamber formed by the openings 17 and extends through the opening 11 in the cap member 7 and is fastened to the cap member at 23. The other end of the fusible element is connected at 25 to an annular collar 27. A compression spring 29 is placed between the collar 27 and a washer 31 at the end of the boric acid disks 15. Electrical connection is made to the fuse 19 from the terminals 9 and 13 by means of a disc 33 which is secured between the sleeve 13 and the cap 9 and a conductor 35 which makes sliding contact with the collar 21. 60

When the fuse element 19 is ruptured at the reduced section 21, the spring 29 withdraws the fuse element from the arc extinguishing chamber formed by the openings 17 and draws the arc in contact with the narrow walls of boric acid. The lower end of the chamber 17 is substantially closed by the fuse element so that the gas given off by the arc extinguishing material 65 70 75

is caused to flow longitudinally through the arc and out the opening 11 in the cap 7.

A condenser which comprises a closed container 37 is secured to the cap 7, thus totally enclosing the opening 11 from the arc extinguishing chamber. The condenser 37 is provided with a large number of metal tubes 38 which remain relatively cold and condense the gases given off by the arc extinguishing material after it has passed through the arc. The provision of the condenser makes possible an expulsion fuse which is totally enclosed, since the gas given off by the arc extinguishing material 15 is condensable at temperatures and pressures which are found in such a fuse, thus reducing the pressure in the condenser and making possible the flow of a large volume of gas even though the device is totally enclosed. This prevents hot ionized gases from being expelled from the fuse and eliminates all danger from flash-over due to the ionized gases coming in contact with adjacent apparatus. At the same time the operation of the fuse is made extremely quiet as compared with the explosive sound which usually accompanies the blowing of an expulsion fuse.

In Fig. 4, wherein parts similar to Fig. 1 are indicated by similar reference characters, there is illustrated the application of my invention to a circuit breaker by the substitution of a pair of contact members 41 and a movable contact rod 43 for the fusible element shown in Fig. 1. The contact members 41 are biased together by springs 45 which make contact with the movable contact rod 43 when in the closed circuit position. The springs 45 are of such dimensions that they do not cause the contact members 41 to close the opening 11 in the cap member 7. The movable contact rod 43 may be actuated to open position by a spring as shown in Fig. 1 and may be provided with a device for holding the contacts in closed position, or may be actuated by any well known circuit breaker operating means.

While I have shown and described a specific embodiment of the invention, it is understood that many modifications and changes may be made without departing from the spirit of the invention as defined in the following claims.

I claim as my invention:

1. In a device the normal function of which is to interrupt an electric current, means between which an arc is established and arc extinguishing means including a solid member adjacent the arc path, said member being of a material which when acted upon by the arc gives off gas substantially all of which is non-inflammable, and means for preventing the free efflux of the major portion of said gas from said member without flowing through the arc path.
2. In a device the normal function of which is to interrupt an electric current, means between which an arc is established and arc extinguishing means including closely spaced walls between which the arc plays, the inner surface of said walls being of a material which when acted upon by the arc evolves gas substantially all of which is non-inflammable, and said walls being substantially impervious to the flow of gas therethrough.
3. In an arc extinguishing device, means normally having a passage therein providing a path for the arc, a cake of solid material along the path of said arc, which when acted upon by the arc gives off water vapor to extinguish the arc and an impermeable wall about said arc path.

4. In a circuit interrupter, an arc extinguishing structure including one or more members of a material which when acted upon by the arc generates gas substantially all of which is non-inflammable, an opening extending through said members, conducting means for interrupting the circuit and causing an arc in said opening, and means for preventing the free efflux of gas from said members except into said opening.

5. In a device the normal function of which is to interrupt a circuit, means between which an arc is established, and an arc extinguishing device having a pair of closely spaced walls between which the arc plays, said walls being of an inorganic, non-hygroscopic material which gives off a non-inflammable gas when acted upon by the arc and leaves a surface which is a good insulator at high temperatures and an impervious wall about said spaced walls.

6. In electrical apparatus, means between which an arc plays in the normal functioning of the apparatus, and an arc extinguishing device having a quantity of boric acid along the arc path to aid the extinction of the arc.

7. In a circuit interrupter, means for causing an arc, means along said arc for continuously evolving a gas substantially all of which is non-inflammable in response to the presence of said arc as long as the arc plays and means for causing said gas to flow longitudinally through the arc to extinguish it.

8. In a circuit interrupter, an expulsion chamber open at one end, means for causing an arc in said chamber, and solid means in said chamber for generating a gas substantially all of which is non-inflammable upon the occurrence of said arc to aid its extinction.

9. In a circuit interrupter, an insulating tube open at one end, electrical terminal members adjacent the ends of said tube, means within said tube for interrupting the circuit between said terminal members and causing an arc, and a solid insulating material adjacent the path of said arc for causing a blast of a gas substantially all of which is non-inflammable longitudinally through the arc and out the open end of the tube.

10. In a circuit interrupter, an insulating tube open at one end, electrical terminal members adjacent the ends of said tube, and one or more members of boric acid along the path of said arc for causing a blast of gas longitudinally through the arc and out the open end of the tube.

11. In a circuit interrupter, an arc extinguishing structure, including a pair of closely spaced walls, conducting means electrically connected in the circuit to be interrupted extending between said walls, said conducting means being separable and having means for relatively moving its parts to draw an arc in contact with said walls, and said walls being of boric acid for giving off a gas when said arc is drawn to extinguish the arc.

12. In a circuit interrupter, an arc extinguishing structure including a pair of closely spaced walls, means for causing an arc between said walls, the breadth of the space between said walls being several times the distance therebetween, and said distance between the walls being so small as to cause the arc to take the form of a thin sheet with a large area in contact with said walls, a portion of said walls being of a material which gives off a gas substantially all of which is non-inflammable to aid the extinction of the arc and an impermeable wall about said arc path.

13. In a circuit interrupter, a rectangular expulsion chamber closed on its sides by walls and having one end open, the distance between an opposing pair of said walls being so small as to cause the arc to take the form of a flat sheet with a large area in contact with said walls, a portion of said walls being of a material which gives off a gas substantially all of which is non-inflammable, and said chamber causing said gas to flow through the arc and out the open end of the chamber to extinguish the arc.
14. In a circuit interrupter, means for causing an arc, solid means for supplying water vapor to the arc, and a condenser for condensing said water vapor.
15. In a circuit interrupter, means for causing an arc, means for supplying an arc extinguishing gas to the arc, and means for condensing said gas, said condensing means being substantially enclosed to prevent escape of said gas and said means for causing the arc having all operating parts thereof within the enclosure preventing escape of said gas.
16. In a circuit interrupter, an arc extinguishing structure comprising an elongated tube open at one end thereof, means within said tube for causing an arc therein, means for causing a blast of a condensable non-metallic gas through the tube to extinguish said arc, and a closed condenser connected to the open end of said tube.
17. In a circuit interrupter, means adjacent the arc path which evolves a gas when acted upon by the arc, substantially all of said gas being non-metallic, non-inflammable and in the liquid state when cooled to room temperatures, and a condenser for condensing said gas.
18. In a circuit interrupter, means for causing an arc, and an arc extinguishing structure having a solid member adjacent the arc, said member being of material which gives off a non-inflammable, non-metallic gas when acted upon by the arc, said gas being condensable at room temperatures and means for condensing said gas.
19. In a circuit interrupter, means for causing an arc, and a cake of solid material along the arc path which when acted upon by the arc gives off water vapor to extinguish the arc, and a device for condensing said water vapor.
20. In a circuit interrupter, an expulsion chamber open at one end, means for causing an arc in said chamber, and solid non-metallic means in said chamber for generating a non-inflammable, condensable gas upon the occurrence of said arc to aid its extinction, and a condenser closing the end of said expulsion chamber.
21. In a circuit interrupter, an insulating tube open at one end, electrical terminal members adjacent the ends of said tube, means within said tube for interrupting the circuit between said terminal members and causing an arc, and non-metallic means along the path of said arc for causing a blast of a condensable gas substantially all of which is non-inflammable longitudinally through the arc and out the open end of the tube, and a condensing device at the open end of said tube.
22. In a circuit interrupter, an arc extinguishing structure, including a pair of closely spaced walls, conducting means electrically connected in the circuit to be interrupted extending between said walls, said conducting means being separable and having means for relatively moving its parts to draw an arc in contact with said walls, and said walls being of boric acid for giving off a gas when said arc is drawn to extinguish the arc, and a device for condensing the gas given off by the boric acid.
23. In a circuit interrupter, an arc extinguishing structure including a pair of closely spaced walls, means for causing an arc between said walls, the breadth of the space between said walls being several times the distance therebetween, and said distance between the walls being so small as to cause the arc to take the form of a thin sheet with a large area in contact with said walls, and a portion of said walls being of a material which gives off a gas which condenses at room temperatures to aid the extinction of the arc, and means for condensing said gas.
24. In a circuit interrupter, an insulating tube open at one end, electrical terminal members adjacent the ends of said tube, one or more members of boric acid in said tube, a rectangular opening extending through said members of boric acid, said rectangular opening having a breadth several times its width, conducting means electrically connected to said terminal members and extending through said rectangular opening, said conducting means being separable and having its parts relatively movable to draw an arc in said opening, the breadth of said opening being so small as to cause the arc to take the form of a thin sheet with a large area in contact with the walls of said opening in the boric acid for causing water vapor to be evolved and flow longitudinally through the arc out the open end of said tube, and a condensing device enclosing said opening at the end of the tube for condensing the water vapor.
25. In a circuit interrupter, means for causing an arc adjacent to a solid material which has the property of decomposing under the influence of heat to evolve a gas and of recombining with said gas when cooled to the vicinity of room temperature, and means for condensing said gas.
26. In a circuit interrupter, means for causing an arc adjacent to a solid material which has the property of decomposing under the influence of heat to evolve a gas and a substantially unvented chamber enclosing said means and said material, said gas being condensable when cooled to the vicinity of room temperature, and means for condensing said gas.
27. In a device the normal function of which is to interrupt an electric current, means between which an arc is established and arc extinguishing means including a solid member adjacent the arc path, said member being of a material which when acted upon by the arc gives off water vapor only, and means for preventing the free efflux of the major portion of said water vapor from said member without flowing through the arc path.
28. In a device the normal function of which is to interrupt an electric current, means between which an arc is established and arc extinguishing means including a cake of solid material along the path of said arc, which when acted upon by the arc gives off gas substantially all of which is water vapor, an impermeable wall about said arc path, and means for causing said water vapor to flow through the arc to extinguish it.
29. In a device the normal function of which is to interrupt an electric current, means between which an arc is established and arc extinguishing means including a pair of closely spaced walls between which the arc plays, said walls being of an inorganic, non-hygroscopic material which gives off a non-inflammable gas when acted upon by the arc and leaves a surface which is a good insulator at high temperatures, an impervious

wall about said spaced walls and means for causing said gas to flow through the arc to extinguish it.

30. In a circuit interrupter, means for causing an arc, means along said arc for continuously evolving a gas substantially all of which is non-inflammable in response to the presence of said arc as long as the arc plays, said gas evolving means along the arc path being an insulator of high resistance at elevated temperatures and means for causing said gas to flow longitudinally through the arc to extinguish it.

31. In a device the normal function of which is to interrupt an electric current, means between which an arc is established and arc extinguishing means including a solid member adjacent the arc path, said member being of a material which when acted upon by the arc gives off gas substantially all of which is non-inflammable, means for preventing the free efflux of the major portion of said gas from said member without flowing through the arc path, and means for causing said gas to flow through the arc path.

32. In a device the normal function of which is to interrupt an electric current, means between which an arc is established and arc extinguishing means including a solid member adjacent the arc path, said member being of a material which when acted upon by the arc gives off gas substantially all of which is non-inflammable and which is an insulator of high resistance at elevated temperatures, and means for preventing the free efflux of the major portion of said gas from said member without flowing through the arc path.

33. In a circuit interrupter, an entirely enclosed chamber, means for initiating an arc adjacent to one end of the chamber, cooling means positioned within the end of the chamber adjacent which the arc is initiated, and means for causing a flow of fluid toward the end of the chamber where the arc is initiated and into said cooling means.

34. In a circuit interrupter, an entirely enclosed chamber, means for initiating an arc adjacent to one end of the chamber, movable means for drawing said arc toward the other end of the chamber and all moving parts of said arc drawing means being within said enclosed chamber, cooling means positioned within the end of the chamber adjacent which the arc is initiated, and means for causing a flow of fluid toward the end of the chamber where the arc is initiated and into said cooling means.

35. In a circuit interrupter, a tubular member of insulating material, an electrical terminal adjacent each end of the tubular member, said tubular member being closed at one end and having a normally closed chamber containing cooling means positioned over the other end thereof, means within the tubular member for normally completing a circuit between said electrical terminals and for initiating opening of the circuit and causing an arc at a point adjacent said cooling chamber, and means for causing a flow of fluid along the tubular member toward the point where the arc is initially caused and into said cooling chamber.

36. In a circuit interrupter, means of insulating material having a tubular passage therethrough, an electrical terminal adjacent each end of the tubular passage, means for normally closing each end of the passage, said closing means for one end of the passage comprising a normally closed metal cooling chamber contain-

ing a plurality of metal cooling members, conducting means extending through the tubular passage, said conducting means being separable for causing an arc, means for elongating said arc in the direction away from said cooling chamber, and means for causing a blast of fluid along the tubular passage and through the arc in the direction toward said cooling chamber.

37. In a circuit interrupter, means of insulating material having a tubular passage therethrough, an electrical terminal adjacent each end of the tubular passage, means for closing each end of the passage, said closing means for one end of the passage comprising a closed metal cooling chamber containing a plurality of metal cooling members, conducting means extending through the tubular passage, said conducting means having a fusible section adjacent the end of the tubular passage closed by said cooling chamber for causing an arc, spring means within the tubular passage for moving one part of said conducting means and drawing the arc back into the tubular passage away from said cooling chamber, and means for causing a blast of fluid through the arc in the tubular passage and into said cooling chamber.

38. In a circuit interrupter, means for causing an arc, means for supplying an arc extinguishing gas to the arc, and means for condensing said gas, said condensing means including means having a large number of spaced portions providing a large area of surface to contact with the gas and cool it and being normally enclosed by a wall member directly surrounding said means providing the large area of surface, and said means for causing the arc having all operating parts thereof within the enclosure formed in part by said wall member of the condenser.

39. In a circuit interrupter, an arc extinguishing structure having a restricted opening therein for confining the arc, conducting means electrically connected in the circuit to be interrupted extending through said restricted opening, said conducting means being separable and having spring means for relatively moving its parts to draw the arc in contact with the wall of said restricted opening, and said wall when acted upon by the arc giving off substantially entirely water vapor to extinguish the arc, and a condenser for condensing said water vapor.

40. In a circuit interrupter, means having a restricted passage therethrough of such small cross section as to hold the arc to a definite path and prevent it from bowing substantially in a lateral direction, means for causing an arc in said restricted passage, means for causing a blast of gas through the restricted passage to extinguish the arc, and a cooling chamber at one end of the passage and into which said gas flows, said cooling chamber comprising a chamber largely filled with metallic means having interstices providing a large surface area to contact with the arc gases, and said chamber being closed at least during operation of the circuit interrupter under ordinary overloads.

41. In a circuit interrupter, means of insulating material having a restricted passage therethrough for confining the arc to a definite path, separable conducting means extending through said restricted passage, a spring for separating said conducting means and establishing the arc in said passage, means for causing a blast of gas through the restricted passage to extinguish the arc, said restricted passage of insulating material holding at least one portion of the arc directly

in the path of said blast of gas, and a cooling chamber at one end of the passage and into which said gas flows, said cooling chamber comprising a chamber which is closed at least during the occurrence of ordinary overloads and having there-in a large mass of metallic means having interstices providing a large surface area to contact with the arc gases.

42. In a circuit interrupter, means for causing an arc, means of solid insulating material defining a restricted passage in which the arc plays, said passage having means for liberating water vapor only when the arc plays therein and said passage being so narrow as to hold the arc in a substantially fixed path and causing the water vapor to flow through the arc with an expulsion action.

43. In a circuit interrupter, means for causing an arc, means of solid insulating material de-

fining a restricted passage in which the arc plays, said passage having means for liberating water vapor when the arc plays therein and said passage being so narrow as to hold the arc in a substantially fixed path and causing the water vapor to flow through the arc with an expulsion action, and a condenser into which the water vapor flows to be condensed.

44. In an arc extinguishing device, a tubular member of insulating material permitting a flow of fluid out therefrom and a quantity of boric acid in said tubular member of insulating material.

45. In a device for a circuit interrupter, a tubular member of insulating material, means for establishing an arc in said tubular member, a quantity of boric acid in said tubular member, and said tubular member permitting a flow of fluid out one end thereof when the arc is drawn.

JOSEPH SLEPIAN.
